UNITED STATES PATENT OFFICE.

MORTEN BALTHAZAR RICHTER, OF COPENHAGEN, DENMARK.

METHOD AND MOLD FOR MANUFACTURING TELEPHONE JACKS.

Application filed March 6, 1923. Serial No. 383,908.

To all whom it may concern:

Be it known that I, MORTEN BALTHAZAR RICHTER, a subject of the King of Denmark, residing at Amaliegade 7, Copenhagen, Denmark, have invented new and useful Improvements Relating to the Methods and Molds for Manufacturing Telephone Jacks; and I do hereby declare the following to be a full, clear, and exact description of the same.

The present invention relates to spring jacks or jack panels to be used in telephone stations and particularly to a method of producing jacks in such a manner that the contact bushes for receiving the connecting plugs are very firmly secured and get exactly uniform and cylindrical contact surfaces, so that the plugs fit smoothly and the life of the jacks is increased.

A further object of the invention is to secure the contact springs adapted to co-operate with the connection plugs simultaneously with and in a manner similar to the fastening of the bushes so as to obtain predetermined relative positions of said springs and bushes.

According to the present invention in manufacturing the jack the bushes are placed each upon an internal cylindrical gauge of the required diameter, these gauges being arranged in a series in a suitable mold, and insulating material in a plastic condition is then pressed around the bushes to force their inner surfaces snugly against the cylindrical surfaces of the gauges and thereby form an insulating strip in which the bushes are rigidly secured after the hardening of the insulating mass. The insulating rear strip may conveniently be pressed simultaneously with the front strip, the contact springs being for this purpose suitably arranged and supported within the mold.

As an insulating material to be used for this purpose cellul (acetyl cellulose) has proved to be well suited. However, other insulating substances may also be used, and I do not wish to limit myself to the employment of any particular insulating material.

The bushes may comprise complete tubes or the metal strips or so-called test springs for connecting the contact bushes with the rear strip of the jack may be made integral with the bushes by stamping out of sheet metal and the part of the stamped material adapted to form the bush is then bent around a cylindrical gauge to form a split bush.

The bushes may conveniently be provided with one or more small projections, perforations or depressions or similar means serving to resist any displacement of the bushes in the insulating mass in order to secure the bushes firmly and rigidly in the insulating strip formed by the pressing operation.

The invention also relates to a mold for carrying out the method explained above, as well as to the jack itself.

The invention is applicable to two-conductor jacks as well as to three or multi-conductor jacks.

An embodiment of a mold for producing a three-conductor jack is by way of example shown on the drawing, in which;

Figure 1 is vertical cross-section through a mold with bushes and springs positioned therein, the dies and the insulating strips being also shown in this figure.

Figure 2 is a fragmental view of the mold seen from below, before pressing, a portion of the lower part of the mold being broken away in order to show the springs.

Figure 3 is a vertical longitudinal section through one end of the mold.

Figure 4 is a perspective view of a bush with integral spring.

The mold shown on the drawing consists of a lower member 1 and an upper L-shaped member 2, one flange of the latter consisting of a downwardly extending portion or reinforcement 3 adjacent to one edge of the member 1. This portion 3 is provided with a series of horizontal bores for receiving the internal cylindrical gauges 4, which can be pushed into the bores. The upper member of the mold is provided with two longitudinally and vertically extending cavities 5 and 6 adapted to receive the insulating material and the dies 7 and 8, it being understood that the dies are adapted to slide up or down in the cavities. 9 indicates the contact bushes with test springs 10.

As explained above, each bush is placed upon a gauge 4. Contact springs 11^a and 11^b adapted to co-act with the connecting plugs are inserted into downwardly open vertical transverse slots produced in longitudinal ribs 13 and 14 extending downward from the upper member 2. The springs 10 are inserted into recesses 12 formed in the lower edges of the ribs 13 and 14.

When the mold is to be made ready for the pressing operation it is turned through 180° with the bottom face upwards, and

the lower member 1 is removed, it being understood that the dies 7 and 8 are not yet inserted into the cavities. The gauges 4 are then inserted through the bores above mentioned, the contact springs are inserted into the said slots, and the bushes 9 are placed upon the gauges, whereupon a flexible wire 15 is passed through holes formed in the inner ends of the gauges, so that by operating nuts 16 screwed on to the outer screw threaded and reduced ends 17 of the gauges, the wire 15 will press against the inner ends of the bushes thereby forcing their outer (foremost) ends 18 tightly against the vertical surface 18 of the reinforcement 3. In this way the foremost ends of the bushes are brought into exact alignment. The contact springs 11^a and 11^b are prevented from displacement lengthwise and maintained in accurate alignment by small pins 19 projecting downwards from the upper mold member 2 and engaging the hooked inner ends of the springs as clearly shown in Fig. 2. It will be understood from the foregoing that the elements 15—19 constitute a means for ensuring a predetermined distance between the foremost end of each contact bush and the contact points 20 of the corresponding contact springs 11^a or 11^b and also for ensuring exact alignment of the various bushes and springs. However, other suitable means may be used for the same purpose. The wire 15 may for instance be replaced by small pins individual to each gauge.

The space for pressing the front insulating strip of the jack is bounded at one side by the surface 18 and at the other side, partly by a rib 22 projecting from the upper member 2 and provided with a series of semi-circular grooves, and partly by a similar rib 21 on the lower member 1. When the mold member 1 is placed in position the opposed semi-circular grooves in the ribs 21 and 22 form together circular holes through which the bushes 9 pass.

When the mold has been prepared as far as described, the lower member 1 is secured upon the upper member 2 by suitable means, not shown on the drawing, and the mold is again turned into its normal position, whereupon a suitable insulating material is filled in predetermined amount into the cavities 5 and 6, and the dies 7 and 8 are inserted into the mold. The mold is then heated to such a temperature, for example 150° C., that the insulating material becomes plastic. In this condition the insulating mass is pressed by means of the pressing dies 7 and 8 and a pressure distributing lever member 32 at a suitable pressure which may for example be about 80 or 90 kilos per sq. cm. The lever 32 may for example be acted upon by pneumatically operated plunger 33. When the pressing

operation has lasted some time the mold is cooled, but the pressing is continued until the mold is hand-warm and the insulating mass is completely hardened, whereupon the mold is separated and the gauges are removed. By this method the bushes are pressed intimately against the cylindrical surfaces of the gauges, and the bushes and the springs are rigidly embedded in the insulating strips 23 and 24 respectively formed by this pressing operation. As shown in Figure 2 the bushes may be provided in their outer surface with small depressions 34, into which the insulating material is pressed during the pressing operation.

In order that the two insulating strips may be subjected to the required pressure per unit of area, which may be different for the two strips, the pressure is applied to the dies 7 and 8 by means of the said lever member 32, which is acted upon at a point A so positioned between the points B and C of engagement of the lever member with the dies 7 and 8 that the lever arms *b* and *c* stand in the required ratio to each other.

Through the upper member 2 of the mold are bored two channels 25 and 26 communicating at their inner ends with the cavities 5 and 6 respectively and also communicating with vertical channels 27 and 28. The connection between each horizontal channel and the corresponding vertical channel is controlled by means of a needle valve 29 formed on a screw 30 provided with a head 31. During the first part of the pressing operation the communication from the interior of the mold to the outer atmosphere is kept open through the channels 25, 27 and 26, 28, so that a small part of the insulating mass is allowed to flow out through these channels until the dies during their downward movement reach a certain index, whereupon the needle valves are closed and the pressing is continued.

If no insulating mass flows out through the channels when the dies have reached a certain point of the downward travel it is hereby indicated that there is not sufficient insulating mass in the mold, and in this case more material must be added.

If bushes without slots are used when carrying out the method according to the invention the cylindrical gauges will mainly serve to maintain the original shape of the bushes, so that the latter are not deformed during the pressing operation.

Figure 4 shows an integral spring and split bush, the latter being provided with small perforations 35 for the purpose explained above.

Having thus fully described my invention I claim as new and desire to secure by Letters Patent:

1. A method of producing telephone jacks

- consisting in placing cylindrical bushes, adapted to receive the connecting plugs, upon individual cylindrical steel gauges arranged in series in a suitable mold, pressing insulating material of the condensation type in plastic condition around the bushes at a substantial pressure sufficiently high to force the inner surface of the bushes into intimate contact with said gauges, allowing 5 said insulating material to become hardened while still maintaining said pressure, and removing said gauges after the hardening of the insulating material to thereby form an insulating strip in which the bushes, properly gauged, are embedded.
2. In the manufacture of telephone jacks a method of producing an insulating strip having cylindrical single-part contact bushes secured therein in alinement, consisting in 10 pressing insulating material containing acetyl cellulose as a main constituent in a plastic condition and at a pressure of about 80-90 kilos per square centimeter and at a temperature of about 150° C. around said bushes 15 while they are held individually upon cylindrical gauges, to tightly press the bushes into intimate contact with said gauges, allowing said insulating material to cool and harden while still maintaining said pressure, 20 and then releasing the pressure and withdrawing the gauges from the bushes.
3. A method of producing jacks for telephone stations consisting in arranging cylindrical gauges of equal diameters in a series 25 in a mold, placing contact bushes for receiving the connecting plugs each upon a such gauge, inserting contact springs in said mold in correct positions relative to said bushes and pressing insulating material around said bushes and springs to thereby form an insulating strip in which the bushes are embedded and another insulating strip in which 30 said springs are embedded.
4. A method of producing jacks for telephone stations consisting in placing contact bushes for receiving the connecting plugs upon cylindrical gauges arranged in a series 35 in a mold, placing contact springs for co-acting with said plugs in the same mold, and pressing insulating material in plastic condition around said bushes and springs by means of two different dies, both 40 operated by a single pressure distributing lever acted upon at a point lying between the points of engagement of the lever with 45 the respective dies, the lengths of the lever arms being so designed relatively to the pressure areas of the dies that the dies will exert predetermined pressures per unit of area.
5. A mold for producing telephone jacks, having formed therein two cavities and comprising means for receiving a series of spaced cylindrical gauges adapted to carry thereon contact bushes for receiving connecting plugs, said bushes being adapted to extend through one of said cavities when the bushes are placed upon the cylindrical gauges, means for accommodating contact springs within the mold, so that they extend 60 through the other of said cavities and pressing means for pressing insulating material contained within said cavities around said bushes and springs.
6. A steel mold for producing the front 65 insulating strip of a telephone jack, comprising a series of parallel cylindrical holes for accommodating a series of spaced cylindrical gauges respectively adapted to carry contact bushes thereon, and means for bringing the outer ends of the contact bushes when placed upon said gauges into exact alignment.
7. A mold for producing telephone jacks, comprising an upper L-shaped mold member 70 having two parallel vertical cavities in its horizontal part for receiving insulating material and dies, and having a series of parallel horizontal holes in its vertical part, said holes being perpendicular to said cavities 75 and adapted to accommodate cylindrical gauges, two dies adapted to fit said cavities respectively and a lower mold member abutting the inner surface of the vertical part of the upper mold member and the lowermost 80 side of the horizontal part of the same and adapted to close said cavities at the bottom thereof, said upper and lower mold members having opposed semi-circular grooves at that cavity nearest to the vertical part of the upper mold member and opposite to the said 85 holes, so that when the said mold members are assembled, after gauges have been inserted through said holes, and contact bushes placed upon the gauges the said semi-circular 90 grooves form together circular apertures fitting closely around the bushes.
- In testimony whereof I have affixed my signature.
- MORTEN BALTHAZAR RICHTER.
